Atty's.

UNITED STATES PATENT OFFICE

ROBERT MAYNE, OF AKRON, OHIO, ASSIGNOR TO THE B. F. GOODRICH COMPANY, OF NEW YORK, N. Y., A CORPORATION OF NEW YORK

MOTION-INDICATING DEVICE

Application filed February 13, 1928. Serial No. 253,922.

This invention relates especially to devices for manifesting breakage of a moving strip of material such as a cord being fed to a rubber coating calender, a loom, or the like, and 5 in a broader aspect it relates to means for manifesting the condition of movement or rest of any body mounted for rectilinear, rotary or other movement.

The present embodiment of the invention 10 has been designed especially for use with apparatus utilizing or operating upon continuous strands of material, to provide simple and positive means for actuating a visible or audible warning signal which preferably is of 15 an electric type, upon the breakage of any one of the strands or the arrival of a trailing end thereof.

The invention also is applicable to rotary apparatus wherein it is desired to break an 20 electric circuit when the speed of rotation falls below a determinate speed.

The chief object of the invention is to provide an improved device of the character described which will be dependent upon movement 25 of the object with which it is associated, and not merely upon the tension of a strand of material, for example, so that a dependable indication of actual movement will be afforded. Further objects are simplicity of 30 construction, small size, positive operation, and avoidance of exposed parts subject to effecting false indications as a result of unintended contacts or movements thereof. Other 35 objects will be manifest in the following description.

In attaining these objects in the preferred embodiments of my invention I provide a signal system including an element adapted to assume and remain in one position in response to and during movement of an adjacent member and to assume a different position when the adjacent member becomes motionless, for actuating the signal system, as 45 by opening and closing an electric circuit.

Of the accompanying drawings:

Fig. 1 is a perspective view of the preferred embodiment of the invention, and a strand of material associated therewith.

Fig. 2 is a vertical longitudinal section of

the same with electrical contact material therein in "make" condition.

Fig. 3 is a similar view with the contact material therein in "break" condition.

Fig. 4 is a diagram of an electrical circuit 55 showing the use of the invention in association with visible and audible warning signals.

Fig. 5 is a sectional view, similar to those of Figs. 2 and 3, of a modified structure in 60 "make" condition.

Referring to the drawing, 10 is a housing of dielectric material which may be suitably mounted upon a machine, and 11 is a cover therefor of like material. The housing 10 65 preferably comprises a unitary structure formed with a generally rectangular internal recess 12 and an arcuate recess 13 which is centrally positioned with relation to the bottom of said recess 12 in communication therewith.

A pair of end-threaded binding-posts 14, 14 comprising the electric terminals of a switch have their lower ends threaded into the housing structure within the recess 12 at 75 opposite ends of the recess 13. Their upper ends extend through respective apertures in the cover 11 and are provided with washers 15, 15 and nuts 16, 16 by which the terminal-clips of electrical conductor-wires 17, 17 are 80 secured to the respective posts, said nuts also serving to hold the cover 11 securely in place upon the housing 10.

Journaled in the side-walls of the housing 10 and extending outwardly therefrom at one 85 side thereof is a shaft 18, and a metal disk 19 having a knurled peripheral face is secured to said shaft within the recess 12, a portion of the disk extending into the arcuate recess 13. Outside the housing 10 the shaft 18 is provided with a peripherally grooved sheave 19 (Fig. 1) adapted, in the embodiment here shown, to be driven by the travel of a strand of material 20 passing around the same, and to become stationary upon breakage of the 95 strand at a more advance part of the strand or upon arrival of the trailing end of the strand.

For making electrical contact between the posts 14, I provide a fluid electrical conductor 100

21 of suitable material such as mercury and of a quantity sufficient normally to fill the arcuate recess 13 and the lower part of the recess 12 and thus electrically to connect the 5 said posts. The posts 14 are made of a material such as steel, adapted to resist the corrosive effect of the mercury, and the latter preferably is covered with a thin film of alcohol to protect it from oxidation or from 10 the effect of corrosive fumes in the atmosphere.

In the operation of the device, when the disk 19 is rotated the level of the mercury will rise at the upwardly moving side of the 15 disk and be lowered at the downwardly moving side of the disk, as shown in Fig. 3, by the impelling force of the rotating disk, so that the mercury is withdrawn from contact with the post 14 at the downwardly moving side 20 of the disk and the electrical contact between the two posts is broken, the fluid conductor then resuming its normal level whenever the disk stops rotating, as in the case of breakage or running out of the cord. The action 25 of the liquid 21 under the impetus of the disk 19 may be likened to a standing wave, surge or swell which effects a local elevating of the fluid in one region and a corresponding lowering or depressing of the fluid in another 30 region, and produces an obliquity of the surface of the fluid which alters the relation of the latter to the electrical terminals.

My invention is not wholly limited to a device adapted to be driven by a cord, as the 35 device may be adapted for the driving of the shaft 18 by other objects whose state of movement or non-movement it is desired to have manifested.

In Fig. 4 is diagrammatically shown a 40 typical electrical circuit employing a plurality of the switch devices for actuating respective visible signals and an audible signal common to the devices. As shown therein, a plurality of the switch devices, each designated as a whole by the numeral 22, normally in "break" condition due to the rotation of their disks, have one terminal of each device connected with a conductor 23 leading from one side of a suitable source of current 45 and have the other terminal of each device connected with a terminal of a corresponding visible signal such as one of a set of lamps 25, 25, the other side of each lamp being connected with a common wire 26 connected through 50 the winding of a solenoid relay 27 and through a wire 28, to the source of current. The armature 29 of the relay 27 is adapted, when actuated, to close a break in a separate 55 circuit 30 having interposed therein an audible warning signal such as an electric bell 31, thus the construction is such that when any one of the switch devices 22 is closed, by stopping of its disk, the lamp individual to the device will be lighted and the 60

bell, common to the several devices, will be caused to ring.

In Fig. 5 is shown a modified switch which is in "break" condition when its disk is motionless and in "make" condition when the disk is rotated in the direction indicated by the arrow thereon. In this embodiment the housing 10^a is formed with a rectangular recess 12^a and an arcuate recess 13^a, the latter being positioned at one end of the rectangular recess, so that the two terminal posts 14, 14 may be mounted at one end of the recess 12^a, at the same side of the rotatable disk 19, as shown. The conductor material 21 is of such quantity as to recede entirely into the recess 13^a and thus break the connection between the posts 14 when the disk 19 is motionless, but to be caused, by rotation of the disk in the direction indicated by the arrow, to assume the position shown in the figure and thus to contact with both posts 14 and provide an electrical connection between them.

Various modifications are possible within the scope of my invention as defined in the appended claims.

I claim:

1. A motion-indicating device comprising a rotary member adapted to be driven by the object of which the state of motion is to be manifested and a body of mercury having its upper surface normally of unitary, plane form so associated with the rotary member as to be caused to assume the form of a standing wave when the rotary member is rotating.

2. A motion-indicating device comprising a pair of spaced-apart electrical terminals, a fluid conductor element having its upper surface normally of unitary plane form adapted to make and break connection between said terminals, and a rotary disk operating upon said conductor element for causing it to change its operative relation to said terminals.

3. A device as defined in claim 2 in which the conductor element is held in contact with the electrical terminals by gravity when the rotary member is stationary.

4. A motion-indicating device comprising a housing, a pair of electrical terminals therein, a fluid electrical conductor therein having its upper surface normally of unitary, plane form, and a rotatable member partly immersed in the latter and adapted, when rotated, to modify the liquid surface thereof to change its relation to said terminals.

5. A motion-indicating device comprising a rotary member adapted to be driven by the object of which the state of motion is to be manifested and a fluid, electrically conductive contactor element having its upper surface normally of unitary, plane form so associated with the rotary member as to be driven by slipping contact therewith and

thus adapted to assume a surface obliquity when the rotary member is rotating and another position when the rotary member is at rest.

⁵ In witness whereof I have hereunto set my hand this 6th day of February, 1928.

ROBERT MAYNE.
